The ornamental design for portable electric drill, as shown and described.

DESCRIPTION

FIG. 1 is a front perspective view of a portable electric drill;
 FIG. 2 is a rear perspective view thereof;
 FIG. 3 is a front perspective view thereof;
 FIG. 4 is a rear perspective view thereof;
 FIG. 5 is a left perspective view thereof;
 FIG. 6 is a right perspective view thereof;
 FIG. 7 is a top plan view thereof; and,
 FIG. 8 is a bottom view thereof.

The broken lines are for illustrative purposes only and form no part of the claimed design.
